UNITED STATES PATENT OFFICE.

HOWARD W. HARLEY, OF PHILADELPHIA, PENNSYLVANIA, ASSIGNOR TO KATE HARLEY, OF PHILADELPHIA, PENNSYLVANIA.

KNITTING-MACHINE NEEDLE.

1,184,526.

Specification of Letters Patent. Patented May 23, 1916.

Application filed October 4, 1915. Serial No. 53,937.

To all whom it may concern:

Be it known that I, HOWARD W. HARLEY, a citizen of the United States, residing in Philadelphia, Pennsylvania, have invented 5 certain Improvements in Knitting-Machine Needles, of which the following is a specification.

The object of my invention is to so construct a reciprocating needle for knitting machines as to lessen the friction due to the reciprocation of the stem or shank of the needle in the corresponding groove of the needle cylinder or other needle carrier. This object I attain by so constructing the 10 needle that the stem or shank of the same will, during its reciprocating movement, be caused to occupy a central position in said groove and will be prevented from coming in forcible contact with either of the walls 15 of the same, thus preventing wearing away of the shank of the needle or the bending or wearing away of the walls of the groove in which it reciprocates.

In the accompanying drawings—Figures 25 1 and 2 are side elevations of knitting machine needles constructed in accordance with my invention, these views also showing in section part of the grooved needle carrier of the machine; Fig. 3 is a section 30 on the line *a—a*, Fig. 1, showing a number of needles disposed side by side in corresponding grooves of the needle carrier; Fig. 4 is a similar section on the line *b—b*, Fig. 2; Figs. 5 and 6 are similar sections illustrating certain modifications of one of the 35 features of my invention; Figs. 7 and 8 are front views, respectively, of Figs. 5 and 6; Fig. 9 is a section, on the line *c—c*, Fig. 3, illustrating one of the needles there shown 40 and its flanking walls; Fig. 10 is a similar section on the line *d—d*, Fig. 4, and Fig. 11 is a view similar to Fig. 7, but showing both upper and lower contact members of the butts similar to the single contact member 45 illustrated in Fig. 4.

The needle shown in Fig. 1 of the drawing is an ordinary type of latch needle composed of wire bent at the three points 2, 3 and 4, so as to form at the base of the shank 50 an offset stem 5 having upon it a forwardly projecting butt 6 for the action of the cams whereby the reciprocation of the needle is effected, and having behind it a recess for the reception of the upturned end 7 of the 55 shank which is reduced in thickness and

bent laterally so as to contact with the opposite walls of the needle groove, as shown in Fig. 9, and thus constitute a spring retainer for preventing accidental longitudinal movement of the needle in its groove 60 when the butt 6 is free from the influence of the cams or other devices which normally act upon the same to effect reciprocation of the needle, such spring member 7 also serving to maintain the shank of the needle in 65 mid position in the groove of the needle carrier, as shown in Fig. 9.

The needle shown in Fig. 2 is of that type which is punched from sheet metal instead of being formed from bent wire, and it is 70 similar in general construction to that shown in Fig. 1, except that the stem 5 does not extend below the butt 6, a rearwardly projecting tongue 6^a being in line with the latter and this tongue having fingers 7^a, one 75 projecting upwardly and one downwardly therefrom, and these fingers being bent laterally so as to bear upon opposite walls of the needle groove, as shown in Fig. 10.

As shown in Fig. 9, the spring finger 7 80 has four bends therein so as to bear upon both walls of the needle groove, both above and below the line of the butt 6, while the fingers 7^a have but single bends therein so that one bears upon one wall and the other 85 upon the opposite wall of the needle groove, although, if desired, each of said fingers 7^a may have a double bend therein similar to that of the finger 7.

In order to prevent the lateral thrust of 90 the cams which act upon the butts 6 of the needles from twisting the shanks of the needles or pressing them forwardly in their grooves so as to contact forcibly with the forward walls of the latter, I provide each 95 of said butts with a laterally projecting contact member or members so as to prevent sidewise displacement of any of the needle shanks 1 in their grooves, such contact members being tapered from their outer to their 100 inner ends in order to reduce the area of frictional contact presented thereby.

In the case of a needle such as shown in Fig. 1, the contact members may consist of shoes 8 (Fig. 3) these shoes embracing the 105 butts 6 of the needles and being soldered or otherwise secured thereto, and each shoe having opposite tapering sides so as to limit the area of contact of the shoes to points at and near the outer ends of the butts 6. 110

The contact members 9 shown in Figs. 2 and 4 consist of tongues which in the first instance projected outwardly from the butts 6 but were afterward bent around to one 5 side of the same, as shown in Figs. 2 and 9, the contact member thus produced bearing at its point of greatest projection against the butt of the adjoining needle or against the root of the finger whereby the contact 10 member of that needle was produced.

In the needle shown in Figs. 5 and 7 the finger which projected beyond the butt was split horizontally preparatory to being bent, the upper member 9^a of said finger being 15 then bent around on one side of the needle butt 6 and the lower member 9^b being bent around on the opposite side of said butt, as shown in Fig. 7, the directions of the bends being reversed on alternate needles so that 20 the upper and lower members 9^a and 9^b of each needle contact with corresponding members of the adjoining needle, as shown in Fig. 7.

Fig. 11 shows a group of needles which 25 are all alike, but in which both the upper and lower contact members project laterally to such an extent that each will contact with the butt of an adjoining needle, as in Fig. 4.

Instead of forming the contact members 30 by means of tongues bent laterally alongside of the needle butt, such contact members may be formed by means of tongues which normally projected vertically from the butt and were afterward turned vertically up 35 or down alongside of the same, as shown for instance at 10^a and 10^b in Figs. 6 and 8.

The contact members are, by preference, in all cases tapered from their outer to their 40 inner portions so as to reduce the area of contact.

I claim:

1. A knitting machine needle having a 45 projecting butt for the action of the operating cams, and a retaining member in the rear of said butt, said retaining member having a laterally bent and elastic portion contacting with one wall of the needle groove above the line of the butt and another laterally bent and elastic portion contacting with the opposite wall of the needle groove 50 below the line of the butt.

2. A knitting machine needle having a 55 projecting butt for the action of the operating cams, and a retaining member in the rear of said butt, said retaining member having, both above and below the line of the butt, a finger laterally bent in opposite directions and presenting two elastic portions, one bearing upon one wall of the needle 60 groove and the other upon the opposite wall of the same.

3. A knitting machine needle having a 65 shank with projecting butt thereon for the action of the operating cams, and a retaining member integral with said shank

and having a laterally bent and elastic portion contacting with one wall of the needle groove above the line of the butt and another laterally bent and elastic portion contacting with the opposite wall of the needle 70 groove below the line of the butt.

4. A knitting machine needle having a shank with projecting butt thereon for the action of the operating cams, and a retaining member integral with said shank and having, both 75 above and below the line of the butt, a finger laterally bent in opposite directions and presenting elastic portions bearing upon the opposite walls of the needle groove.

5. A knitting machine needle having a shank with forwardly offset portion at its 80 lower end carrying a forwardly projecting needle butt, and a retaining member disposed in said offset and having a laterally bent and elastic portion contacting with one 85 wall of the needle groove above the line of the butt and another laterally bent and elastic portion contacting with the opposite wall of the needle groove below the line of the butt.

6. A knitting machine needle having a shank with forwardly offset portion in its lower end carrying a forwardly projecting needle butt, and a retaining member disposed in said offset and having, both above 90 and below the line of the butt, a finger laterally bent in opposite directions and presenting elastic members, one contacting with one wall and the other with the opposite wall of the needle groove.

7. A knitting machine needle having a shank with forwardly offset portion at the lower end carrying a forwardly projecting butt, and a retaining member disposed in said offset and integral with the offset portion of the shank, said retaining member having a laterally bent and elastic portion contacting with one wall of the needle groove above the line of the butt, and another laterally bent and elastic portion contacting with the opposite wall of the needle 105 groove below the line of the butt.

8. A knitting machine needle having a shank with forwardly offset portion at the lower end carrying a forwardly projecting butt, and a retaining member disposed in said offset and integral with the offset portion of the shank, said retaining member having, both above and below the line of the butt, a finger laterally bent in opposite directions and presenting elastic portions, one bearing upon one wall and the other upon the opposite wall of the needle groove.

9. The combination of a knitting machine needle having a shank with projecting butt, 125 and a member carried by said butt and projecting laterally therefrom so as to contact with part of the butt of an adjoining needle in the machine, said contact member having its point of greatest lateral projection at and 130

near the outer end of the butt and decreasing in the extent of such projection toward the base of the butt.

10. A knitting machine needle having a shank with projecting butt thereon, and a laterally bent member integral with said butt and projecting laterally therefrom so as to contact with part of the butt of an adjoining needle in the machine, said contact member having its point of greatest lateral projection at and near the outer end of the butt and decreasing in the extent of such projection toward the base of the butt.

11. A knitting machine needle having a shank with projecting butt thereon, and a pair of laterally bent members integral with said butt, one projecting on one side and the other on the opposite side of the latter, and each serving to contact with part of the butt of an adjoining needle in the machine, each of said contact members having its point of greatest lateral projection at and near the outer end of the butt and decreasing in the extent of such projection toward the base of the butt.

12. A knitting machine needle having a shank with projecting butt thereon, and a member integral with said butt and bent alongside of the same so as to contact with part of the butt of an adjoining needle in the machine, said contact member being gradually reduced in thickness from the outer portion of the butt toward the base of the same.

35 13. A knitting machine needle having a

shank with projecting butt thereon, and upper and lower members integral with said butt and one bent to one side and the other to the opposite side of the same so as to contact with part of the butt of an adjoining needle in the machine, each of said contact members being reduced in thickness at and near the base of the butt.

14. A knitting machine needle having a shank with projecting butt thereon, and upper and lower members integral with said butt and one bent to one side and the other to the opposite side of the same so as to contact with part of the butt of an adjoining needle in the machine, each of said contact members being tapered in thickness from the outer end of the butt to the base of the same.

15. The combination, in a knitting machine, of a series of needles each having a shank with projecting butt, and each butt having upper and lower laterally bent fingers integral therewith and disposed one on one side and the other on the opposite side of the butt, said needles being so disposed that the upper and lower members will contact with like members of adjoining needles.

In testimony whereof, I have signed my name to this specification, in the presence of two subscribing witnesses.

HOWARD W. HARLEY.
